Primary Examiner — Dana L Meyrow(74) *Attorney, Agent, or Firm* — Sheridan Ross P.C.(57) **CLAIM**

The ornamental design for a metal bottle, as shown and described.

DESCRIPTION

FIG. 1 is a front perspective view of the metal bottle; FIG. 2 is a front elevation view thereof; FIG. 3 is a top plan view thereof; and, FIG. 4 is a bottom plan view thereof. The broken lines in the drawings illustrate the portions of the metal bottle that form no part of the claim.
